(57) **CLAIM**

The ornamental design for a belted track assembly, as shown and described.

DESCRIPTION

FIG. 1 is a top, front, right perspective view of a belted track assembly showing my new design;

FIG. 2 is a front perspective view thereof;

FIG. 3 is a rear perspective view thereof; and,

FIG. 4 is a top view thereof and wherein the bottom, right and left side views are identical with each depicting the repeating pattern of the lugged track surface.
